UNITED STATES PATENT OFFICE.

WILLIAM L. SECHLER, OF BRADDOCK, PENNSYLVANIA.

PROJECTILE-PROTECTOR.

1,239,309.

Specification of Letters Patent.

Patented Sept. 4, 1917.

Application filed January 16, 1917. Serial No. 142,733.

To all whom it may concern:

Be it known that I, WILLIAM L. SECHLER, a citizen of the United States, residing at Braddock, in the county of Allegheny and 5 State of Pennsylvania, have invented certain new and useful Improvements in Projectile-Protectors; and I do declare the following to be a full, clear, and exact description of the invention, such as will enable 10 others skilled in the art to which it appertains to make and use the same.

My invention has for its object to provide an extremely simple and inexpensive yet an efficient and durable device for encompassing 15 the usual copper packing rings of projectiles to guard the same against injury during handling and transportation, and with this general object in view the invention resides in the novel features of construction and 20 unique combinations of parts to be herein-after fully described and claimed, the descriptive matter being supplemented by the accompanying drawings which constitute a part of this application, and in which,

25 Figure 1 is a side elevation of a projectile showing the application of one of the protectors thereto;

Fig. 2 is an enlarged longitudinal section of the protector applied;

30 Fig. 3 is a vertical transverse section on the plane of the line 3—3 of Fig. 1 showing more particularly the construction of the split laminated ring and the joint for securing the ends thereof together under ordinary 35 circumstances;

Fig. 4 is a detail section similar to the upper portion of Fig. 3, but showing the manner in which the joint may be severed;

Fig. 5 is a duplicate of Fig. 1 with the 40 exception that it illustrates a different form of protector;

Fig. 6 is a longitudinal section of the protector shown in Fig. 5;

Fig. 7 is a rear end elevation thereof with 45 parts broken away and in section;

Fig. 8 is a detail section similar to the upper portion of Fig. 3 showing a slightly different form of construction; and

Fig. 9 is a detail transverse section 50 through main guard ring, showing another manner in which the same may be constructed.

In the drawings above briefly described, the numeral 1 designates a common type of 55 projectile while 2 has reference to the usual

copper packing ring at the rear end thereof, said ring being provided with the usual grooves 3 which are packed with grease before shipment of the projectile. It is the object of the present invention to retain this 60 grease in the grooves and prevent the entrance of dust and the like thereto as well as to guard the ring 2 against injury during handling or transportation. To attain these results, the improved protector may be 65 constructed in a number of ways, but its essential features are a main continuous guard ring 4 to surround the rear end of the projectile in abutting relation with the rear edge of the ring 2, an auxiliary and 70 split guard ring 5 to surround said projectile in contact with the front edge of the ring 2, and a split flexible collar 6 extending between and secured to the two rings 4 and 5.

In Figs. 2, 3 and 4, the ring 4 is shown of laminated construction, the laminations 7, with the exception of the outermost thereof, being in the form of split rings preferably formed of wood fiber with the grain of contacting rings running in opposite directions to gain strength. Alternate laminations 7 extend beyond the intervening laminations, as shown clearly in Figs. 3 and 4, so that practically a tongue and groove joint is provided between the two ends of the ring 4, this joint being free to spring open as indicated in Fig. 4 when the outer lamination 8 is severed, if it should be desirable to remove the ring 4 in this manner. Said lamination 8 is the only one of the series which is continuous, the two ends thereof being riveted together by a rivet 9 while other rivets 10 extend through the several laminations to secure them together. 90

The rivets 10 also pass through one edge of the canvas or the like of which the collar 6 is constructed, said edge being interposed between certain of the laminations 7 of the guard ring 4 so that the latter projects both 100 inwardly and outwardly from said collar to more or less guard the latter when the projectile is being rolled from one point to another. The sheet of material from which the collar 6 is formed, is passed around the auxiliaries 11 and the free edge portion is secured by several rows of stitching 12 to the inner face of the collar proper, so that an annular hem is provided in which a circumferentially corrugated ring 13 of 110

fiber or the like is located to assist the collar in guarding the packing ring 2 against injury.

The auxiliary guard ring 5 is by preference constructed of several layers or laminations of fiber, the ends of which are in no way joined but are alined substantially with the split 13 of collar 6, a strap 14 being provided for normally holding the ends of said ring 5 in abutting relation to retain the entire device on the projectile. When this strap is released, ring 5 expands so that the entire protector may be moved rearwardly to detach it from the projectile. Obviously, reversal of this operation is necessary when attaching the devices.

If for any reason the protector must be removed with the loss of as little time as possible, both the strap 14 and the outermost lamination 8 of the guard ring 4 will be cut with a knife or other suitable tool, said lamination being severed adjacent the meeting ends of the other laminations 7 so that the ring 4 will expand to the position indicated in Fig. 4. The entire protector is thus free to be quickly withdrawn from the projectile.

In Figs. 5, 6, 7 and 8 the construction is substantially the same as that above described. In these figures, however, the outermost lamination 8' of the main guard ring 4 is tapered at its ends so as to form a joint which will offer no obstruction to rolling the shell. In this type of the invention the material of which the collar 6 is formed is folded around the ring 4 as well as the auxiliary ring 5, the outer and inner portions of the folded material being stitched together at 11' so that an annular seam is formed in which one of the rings or bands 12 is located.

Another point of difference between this type of the device and that above described is that the strap 14 is eliminated in favor of a cord or small rope 14' passed around the collar 6 adjacent the ring 5 with its ends tied together. This cord may be either untied or cut to permit the device to be removed, and whenever required the lamination 8' may be severed so as to permit the entire device to expand as above described.

As a modification of the ring 4, it is shown in Fig. 9 as constructed of a main body 15 of wood, a number of laminations 7' secured in contact with the inner face of said ring, and an outer lamination 8'' corresponding to the parts 8 and 8' above described. This form of ring may be preferable in some instances since it will not only be less expensive to manufacture but will be much stronger than rings constructed totally of fiber.

When the improved devices are applied, the main and auxiliary rings 4 and 5 as well as the collars 6 and rings 12 effectively serve to guard the packing ring 2 against injury.

and prevent the entrance of dust and grit into the grease in the grooves 3. The protector is therefore highly efficient regardless of its simplicity and inexpensive construction and may be removed instantly when required. For these reasons the constructions shown and described constitute the preferred forms of the device but it is to be understood that within the scope of the invention as claimed, numerous changes may be made without sacrificing the principal advantages.

While I have shown and described the invention as being applied to the projectile from its rear end which of course is the most practical way, since it may be done while the projectile is held by a grapple, it will be understood that the invention may be applied from the tapered or front end of the projectile, or used in the position reverse from what is shown in the drawings.

I claim:—

1. A protector for the packing bands of projectiles comprising a main guard ring to surround the projectile in contact with the rear edge of said packing band, said guard ring being of a thickness to project beyond the periphery of said packing band, an auxiliary guard ring to surround the projectile in contact with the front edge of the packing band, said auxiliary ring being likewise of a thickness to project beyond the periphery of the packing band, and a collar to surround said packing band, the edges of said collar being secured to said main and auxiliary guard rings.

2. A protector for the packing bands of projectiles comprising a main guard ring to surround the projectile in contact with the rear edge of said packing band, said guard ring being of a thickness to project beyond the periphery of said packing band, an auxiliary guard ring to surround the projectile in contact with the front edge of the packing band, said auxiliary ring being likewise of a thickness to project beyond the periphery of the packing band, a collar extending between and secured at its edges to said main and auxiliary guard rings, said collar being adapted to circumscribe said packing band and having an annular hem located between said guard rings, and a cushioning ring in said hem.

3. A protector for the packing bands of projectiles comprising a main guard ring to surround the projectile in contact with the rear edge of said packing band, said guard ring being of a thickness to project beyond the periphery of said packing band, an auxiliary guard ring to surround the projectile in contact with the front edge of the packing band, said auxiliary ring being likewise of a thickness to project beyond the periphery of the packing band, a collar extending between and secured at its edges to

- said main and auxiliary guard rings, said collar being adapted to circumscribe said packing band and having an annular hem located between said guard rings, and a circumferentially corrugated cushioning ring of yielding material in said hem.
4. A protector for the packing bands of projectiles comprising a continuous main guard ring to surround the projectile in contact with the rear edge of said packing band, an auxiliary and split guard ring to surround said projectile in contact with the front edge of said packing band, means for securing the ends of said auxiliary ring in close relation, and a protecting collar secured at its edges to said main and auxiliary rings, said collar being split transversely in substantial alinement with the meeting ends of said auxiliary guard ring.
5. A protector for the packing bands of projectiles comprising a guard ring to surround the projectile in contact with one edge of said packing band, said ring consisting of an annular body with its ends disconnected and a layer of severable material secured to the ends of said body and adapted to be cut adjacent the ends thereof to permit the entire guard ring to expand, and a flexible split collar extending from said guard ring and of a width to totally cover and surround the packing band.
6. A protector for the packing bands of projectiles comprising a guard ring to surround the projectile in contact with one edge of said packing band, said guard ring consisting of an annular body composed of a plurality of laminations in the form of split rings, the ends of alternate laminations extending beyond the ends of the intervening laminations to form an endwise separable joint between the two ends of said body, a continuous ring surrounding said body and adapted to be cut adjacent the ends thereof to permit the entire guard ring to expand, and a split collar extending from said guard ring to surround the packing band.
7. A protector for the packing bands of projectiles comprising a collar composed of inner and outer layers of material, means for securing said collar in place around said packing band, and a ring formed of resilient material and corrugated circumferentially, said ring being located between said thicknesses of material.
8. A protector for the packing bands of projectiles comprising a guard ring to surround the projectile in contact with the rear edge of its packing band, said guard ring being of a thickness to project beyond the periphery of said packing band, a collar of flexible material extending from said guard ring and of a width to cover said packing band, and means at the free end of said collar to draw it into engagement with the front edge of said packing band.
9. A protector for the packing bands of projectiles comprising a guard ring to surround the projectile in contact with the rear edge of its packing band, said guard ring being of a thickness to project beyond the periphery of said packing band, a collar of flexible material extending from said guard ring and of a width to cover said packing band, said collar being slit transversely, a bead extending around the front edge of said collar and adapted to engage the front edge of said packing band, and means for tightening said slit collar upon the packing band.
10. A protector for the packing bands of projectiles comprising a guard ring to surround the projectile adjacent said packing band, said guard ring consisting of an annular body composed of a plurality of laminations in the form of split rings, the ends of alternate laminations extending beyond the ends of the intervening laminations to form an endwise separable joint between the two ends of said body, and a strip of severable material secured to the meeting ends of said body and adapted to be cut to permit the guard ring to expand for quick removal from the projectile.
- In testimony whereof I have hereunto set my hand in the presence of two subscribing witnesses.
